COMPRESSOR UNIT

Frederick J. Heideman, Rochester, N. Y.

Application June 4, 1931, Serial No. 542,181

14 Claims. (Cl. 230—175)

My present invention relates to electric refrigerating units, such as the motor driven installations designed for domestic use, and it has for its object to provide a small compact refrigerating plant having the general proportions of the ordinary icebox and which will operate quietly and without noticeable vibration. My improved refrigerator embodies the principle of circulating a volatile liquid, such as sulphur dioxide. The evaporation thereof in the refrigerating chamber lowers the temperature thereof and the gas is drawn off by a compressor, discharged into a high compression chamber, cooled by exposure to radiation after absorbing the heat incident to compression and thus condensed and liquefied again is returned to the first mentioned chamber. The improvements are directed in part toward the construction of the compressor itself and particularly a system of controlling valves associated therewith to produce the desired circulation, which valves are of a nature rendering them both extremely durable and quickly effective in action. The improvements are further directed toward the provision of a simple and effective lubricating system for the moving parts, toward the utilization of this lubricating system for reducing the load on the motor until it has picked up speed, and toward a particular mounting of the motor that reduces both noise and friction to a minimum.

To these and other ends, the invention resides in certain improvements and combinations of parts, all as will be hereinafter more fully described, the novel features being pointed out in the claims at the end of the specification.

In the drawings:

Fig. 1 is a vertical central section, partly in elevation, through a refrigerating unit constructed in accordance with and illustrating one embodiment of my invention;

Fig. 2 is an enlarged horizontal section taken substantially on the line 2—2 of Fig. 1;

Fig. 3 is a fragmentary horizontal section on the scale of Fig. 2 taken substantially on the line 3—3 of Fig. 1;

Fig. 4 is an enlarged fragment of the showing of Fig. 1;

Fig. 5 is a transverse fragmentary section taken substantially on the line 5—5 of Fig. 4;

Fig. 6 is a fragmentary section taken substantially on the line 6—6 of Fig. 4;

Fig. 7 is a fragmentary section, enlarged, taken on the line 7—7 of Fig. 4;

Fig. 8 is a fragmentary plan view of a portion of the mounting plate;

Fig. 9 is an enlarged section through the compressor taken on the line 9—9 of Fig. 4;

Fig. 10 is a similar view showing the parts in other relative positions and at another point in the cycle of movement;

Fig. 11 is a vertical section on the line 11—11 of Fig. 9, and

Fig. 12 is a top view of the compressor cylinder block.

Similar reference numerals throughout the several views indicate the same parts.

The general design of the embodiment of the invention illustrated contemplates the location of the motor, compressor and condenser on top of the insulated box containing the refrigerating chamber and in the general view of Fig. 1, only a portion of the top of the box is shown at 1, the refrigerating chamber being indicated generally at 2. This upper outer wall of the box may be of the usual or any desired heat insulating construction but for the purposes of my invention, it is provided with a large circular central well or opening 3, through which the heat-absorbing element of my machine depends from the connected structure of the aforesaid elements resting on top, all being in an assembled unit. To these ends, the well is spanned and covered by a mounting plate or table 4, its marginal contact with the top of the box 1 being made air-tight of its own weight by a suitable packing ring or gasket 5. Secured to flanges 6 on the underside of the plate is a cylindrical casing 7 that is preferably of about the thickness of the top 1 and similarly heat-insulated, as by a filling of balsam wool 8. The attachment to the lugs 6 is made through the medium of side wall 9.

Secured to the table 4 and extending downwardly through tubes 10 in the member 7 are a plurality of posts 11 having nuts 12 at their lower ends supporting hanger brackets 13. These latter are fastened to the heat-absorbing unit 14, which is thus suspended close to the top of the refrigerating chamber 2. It is shown in the present embodiment provided with a central open ended chamber 15 for the accommodation of the usual ice trays 16.

The element 14 has double walls 17 and 18 forming a jacket surrounding the chamber 15, and in this chamber, to a level indicated approximately at L in Fig. 1, the liquid body of sulphur dioxide or corresponding heat transfer element is collected and maintained as delivered from the condenser hereinafter described. The proper and desired level is established and kept substantially uniform in the following manner.

A drain pipe 19 extending downwardly from the condenser through a tube 20 in element 7 is connected by an elbow 21 with a head 22 in one end of the liquid container 14. The head is provided with a valve seat 23 opened and closed by the horizontal movement of a needle valve 24. This needle valve is pivoted at 25 to an upwardly extending arm 26 projecting rigidly from a hinge bracket 27 fixed to a float 28 and pivoted at 29 to a lug on the head 22. When the level of the liquid L drops sufficiently, the float 28 will obviously drop with it and withdraw or open the valve 24, feeding in more liquid that is meanwhile collected in the drain pipe 19. When the level has been restored, the valve, of course, is closed in the manner of any float control. Lowering movement of the float to a degree greater than is necessary to adequately open the valve is prevented by a stop lip 30 on the hinge bracket 27 which abuts against the lug carrying the pivot 28.

The condenser itself is shown to consist of a cylindrical body of helically coiled pipe 31 of suitable capacity and radiating surface which is enclosed within and suitably mounted on a surrounding protecting grid or cage 32 resting on the box top 1 through a band 33, through which grid air is free to circulate. The aforesaid drain pipe 19 extends through the table 4 and connects with the lower convolution of the condenser pipe at 34, whereas the intake pipe 35, the connections of which will be hereinafter explained, connects with or forms a continuation of the top convolution. The range of piping is such that there is always sufficient liquid backed up therein to supply the heat-absorbing element 14.

The motor and compressor are hermetically sealed within a dome 36 constituting the compression chamber. It embodies a base pan 37 supported upon the table 4 through the medium of coiled compression springs 38 upon the table 4, headed guide bolts 39 being secured in spring centering lugs 40 and extending slidably through the table in spring centering depressions 41. The structure is thus held against lateral displacement while floating resiliently on the springs. This is to absorb vibration from the motor and other moving parts.

A base plate 42 is secured to the bottom of the base pan 37 as by the screws 43 and supported upon it in accurately spaced relationship is a casting forming a superstructure 44. It is spaced by means of spacing sleeves 45 and secured rigidly to the base plate 42 by bolts 46 extending through the sleeves. A hub 47 rising centrally from and integral with the superstructure 44 provides a long vertical bearing for the direct drive crank shaft 48 of the motor to be hereinafter described. A crank disk 49 on the lower end of this shaft occupying a cavity 50 in the bearing piece but spaced from the walls thereof carries the crank pin 51 having a bearing in a projecting bearing lug 52 at the head of a reciprocating and oscillating cylinder 53. This cylinder cooperates with, in the usual manner, and is hence guided upon an oscillating piston 54 having a bearing at 55 on a fixed wrist pin 56 secured in and extending between the base plate 42 and the superstructure 44. The cylinder also has a close sliding fit with both of the last mentioned elements, being in the form of a rectangular block, as shown in Fig. 5. The exhaust port for this working couple is indicated at 57 and is normally closed by a wafer valve 58 that occupies a shallow cavity 59 in a lug 60 adjacent to and communicating with the cav-

ity 50. It is held in place by bending its ends 61 up over the lug and is displaced by the pressure of exhaust gas against the tension of springs 62 arranged in pockets above the valve.

The discharge from the compression is thus admitted to the interior of the dome 36 and as the pressure builds up is discharged through an elbow connection 63 to the intake elbow 35 of the condenser 31 before described. To reduce the heat generated in the compression dome 36 as far as possible before the heated gas enters the condenser, I provide a series of radiating fins 64 on the lateral cylindrical walls of the dome. These are clearly shown in Fig. 2 to consist of hollow U-shaped ribs having oppositely turned base flanges 65 that abut in adjoining units and may be spot welded to the chamber or dome wall.

To return to the compressor couple, the intake port in the cylinder head 53 is indicated at 66 communicating on the underside of the cylinder block with an arcuate or kidney-shaped passage or cavity 67 on the cylinder bearing surface of the base plate 42. That is, it is adapted to and does so at times with the oscillation of the cylinder for the motion of the latter relatively to this arcuate passage constitutes the only intake valve element for the compressor, as will be later described. Also communicating with the passage 67 from the bottom, as clearly shown in Figs. 4 and 8, is a passage 68 leading to a cavity or chamber 69 in the base tray 37, that is sealed by the base block 42 through which the said passage extends, a gasket 70 being provided to be clamped by the screws 43.

In the bottom of chamber 69 is formed a trap 71 for a purpose hereinafter explained. This trap is partially covered by a cap plate 72 having a central opening 73 provided with a surrounding collar that centers a spring 74 which holds a wafer valve 75 normally against a valve seat surrounding an opening 76 in a boss 77 on the bottom of the base tray 37 and into this boss is threaded a connection 78 on the upper end of a pipe 79. This pipe extends through a tube 80 in element 7, is looped at 81 to give it flexibility 45 in view of the spring mounting 38 of the base pan and has an elbow connection 82 communicating with the liquid jacket 17-18 at the top of the chamber 14.

Returning to the intake port 66 in the cylinder block 53 of the compressor, this port is so positioned with reference to the reciprocatory and oscillatory combined movements of the cylinder that it cooperates with the arcuate passage 67 to function as a valve or cutoff in the following manner. Its movement is generally concentric with the arcuate passage 67, though not exactly so due to the peculiar path produced by the combined movements referred to. When the cylinder has completed its compression or exhaust stroke, as in Fig. 4, the port 66 is in the closed position indicated at A in Fig. 8. It remains closed for an instant as the crank and cylinder move off of the dead center and then rides into communication with arcuate passage 67, so that on the quarter point of the cycle it is in the position B. On the next quarter, it remains in open communication until the dead center position C is approached, at which point it closes again and remains closed for the remaining half of the cycle back to the point A, during which time, of course, the charge of gas is being discharged from port 57 through valve 58 and into the enclosed chamber. It is obvious that this intake charge is drawn from the volatilized gas in the 75

heat absorbing chamber 14 above the liquid through pipe 81 to chamber 69, raising valve 75, to passage 68 and thence to passage 67.

The prime mover for the crank shaft 48 is preferably a split phase motor of suitable design contained within the dome 36. It is mounted upon the superstructure 44 in the following manner:

Preferably integral with and rising from the margin of the casting 44 is a circular series of posts 83 carrying an also preferably integral ring 84, upon which ring is supported in a case 85 the field windings or laminations 86 of the stator. The posts 83 are connected by ribs 87 with the bearing 47. A hub 88 is clamped to the reduced upper end 89 of crank shaft 48 by means of a cap nut 90 and is also preferably splined thereon. It has a bearing on the upper end of the bearing hub 47 and carries the windings or laminations 91 of the rotor. Normally and when the motor is at rest, the rotor and stator are in the relative positions of Fig. 1, that is, with the former in a lowered position resting on the bearing hub. When energized, the tendency of the element 91 is to rise and center itself in the magnetic field, of course, raising the crank shaft with it, which latter is permitted due to the before explained freedom of movement of the crank disk 49 in the cavity 59. The motor thus floats freely vertically on the long bearing that the crank shaft is provided with in the bearing member 47, greatly reducing vibration and friction as well. There is no necessity for providing the crank shaft with a thrust bearing.

In sealed machines of this character, the matter of lubrication is, of course, an important factor, and I have provided an improved lubricating system which is so worked in with the gas compressor that it performs the added function of reducing the load on the motor, initially, or until it has picked up momentum. I will first describe the oiling system as such.

A body of oil is maintained in the bottom of the gas chamber 36, which means in the base tray 37, at a level slightly above the bottom of the piston 54. This directly lubricates the piston and cylinder of the compressor as well as the bearing of the former on the wrist pin 56 and the bearing of the cylinder block 53 on the base plate 42. Incorporated in the cylinder block 53 below the compressor piston and offset therefrom, as shown in Figs. 4 and 5, is an oil pump cylinder chamber 92 occupied by a piston rod 93. This piston rod likewise has a bearing 94 on the fixed wrist pin 56 and swings parallel and in unison with piston 54 with the movements of the cylinder block. The intake port for this oil pump is in the side of the cylinder block beneath the oil level and, as indicated in dotted line, for instance, in Figs. 5 and 10. The end of the pump cylinder 92 is in communication with the vertical passage 95 in the cylinder block (Figs. 4 and 11) plugged at the bottom at 96 and provided with an intermediate check valve 97. This passage in turn communicates with a transverse horizontal passage and chamber 98 in the cylinder block. A port 99 leads from chamber 98 to the bearing of the crank 51. The latter is bored axially to form an oil passage 100, which passage is plugged at the bottom and extends, eccentrically of course, quite a distance into the crank shaft 48. A partial circumferential passage 101 on the crank pin registers intermittently for a period on the rotation of the crank with the port or passage 99 and transmits oil therefrom under pressure to axial passage 100

through a radial connecting passage 102. The oil passes from the upper end of passage 100 through a radial port 103 to a cavity 104 in the bearing 47 communicating with helical passages 105 formed in the bearing surface of the upper portion of the crank shaft. This last named passage finally delivers to the bearing point of the rotor hub 88, where the oil is forced out to drain back into the gas chamber indiscriminately for general lubricating purposes. As the crank shaft is lifted by the rotor, the oil is discharged more freely and is thrown all about.

I now come to an explanation of the manner in which this oiling system or certain elements thereof are utilized to reduce the starting load on the motor. The cross chamber 98 (plugged at both ends, as indicated at 106 and 107) contains a sliding piston valve 108 having a spacing point 109. A spring 110 reacting against plug 106 normally holds this valve in the position of Figs. 9 and 11, in which it closes the port 99 and prevents the oil column in the crank shaft above that point from running back. This is when the mechanism is at rest and the stop point 109 abuts the plug 107, so that the oil passage 95 in the oil pump is always open. A diagonal relief port 111, best shown in Fig. 4, is drilled in the top of the cylinder head 53 to communicate with the chamber 98 in rear of the piston valve in the position of Fig. 9, said relief port opening into the gas chamber 36. A bypass port 112 also connects the compression chamber of the cylinder block with chamber 98 opposite the relief port. The operation and function of this group of ports, valves and passages is best understood by reference to Fig. 4 and Figs. 9 to 12, and is as follows:

Starting with the position of rest shown in Figs. 9 and 11, when the motor is energized, on the first few revolutions of the crank shaft and reciprocations of the cylinder block, no compression of the gas drawn in from the intake port 66 occurs because it escapes freely through the bypass port 112, the chamber 95 and the relief port 111. In fact, no gas is drawn in at 66 because instead gas under pressure from chamber 36 rushes in through relief port 111, chamber 98 and bypass 112 on the suction stroke of the compressor. Thus, the pressure is balanced for the time being between the compression chamber and the surrounding gas chamber, and the normal working load is not imposed upon the motor.

In the meantime, however, the oil pump 92-93 operates effectively on the first movement and starts to build up oil pressure in the chamber 98 in front of the piston valve 108. The latter, therefore, gradually recedes against the tension of spring 110 to the position of Fig. 10, in which it opens the oil port 99 to the lubricating ducts of the crank and crank shaft and closes the bypass 112 and relief port 111. By this time, the motor has gained sufficient to accept the load and the compressor functions in the normal manner through discharge port 57 and valve 58. When the motor comes to rest again, the spring 110 returns the piston valve to the position first described.

It might appear that the spring 110 would be insufficient to return the piston valve against the body of oil trapped between the port 99 and the check valve 97. In practice, I provide against this by making the piston valve slightly undersize in its fit within the passage 98, so that this trapped oil can leak or seep past it, which is sufficient particularly in view of the

fact that the periods of rest are of substantial duration.

The motor is, of course, controlled in the usual manner in such devices by a make and break in the field actuated by pressure or the balancing of interior and exterior temperatures, but such devices are so well known to those skilled in the art that it is thought unnecessary to show or describe it herein.

10 The wafer valve 71 in the intake gas line and supply pipe 79 is for the purpose of trapping any oil escaping into the chamber 69.

While it is necessary to maintain a tight sliding contact of the cylinder block 53 upon the base plate 42 to make the intake cutoff effective, so carefully a machined contact between the top of the cylinder block and the underside of the superstructure casting 44 is not required, inasmuch as the spring pressed exhaust valve 58 maintains a close contact to cut off the exhaust port 57 when required. The block is otherwise amply guided.

15 The enclosing grid 32 for the condenser I prefer to make as indicated of expanded metal mesh and effect a fused metallic connection between it and the convolutions of the condenser pipe 34 which it supports, the connection being not necessarily continuous but at frequent intervals. This makes more intimate the thermal conductivity between them, increasing the radiation and distributing the heat absorption. The cage or grid and condenser so shown in the drawings induces circulation but is designed for use in otherwise still air.

20 35 I claim as my invention:

1. In a gas compressor for circulatory refrigerating systems, the combination with an oscillatory piston, and a reciprocating and oscillatory cylinder cooperating therewith and provided with an exhaust port and an intake port, of means in direct relative sliding contact with the cylinder for opening and closing the intake port embodying a passage having a form substantially coincident with the path of the intake port as a result of the combined movements of the cylinder.

2. In a gas compressor for circulatory refrigerating systems, the combination with an oscillatory piston, and a reciprocating and oscillatory cylinder cooperating therewith and provided with an exhaust port and an intake port, of a base block upon which the cylinder slides provided with an arcuate passage on its surface and in the intake line, said passage being in conformation with a portion of the path of the intake port to open and close the same.

3. In a gas compressor for circulatory refrigerating systems, the combination with a base plate having a passage therethrough, of an oscillatory piston, and a reciprocating and oscillatory cylinder block having a flat face provided with an intake port movable into and out of register with the passage to be opened and closed by the block, said cylinder being provided with an exhaust port.

4. In a gas compressor for circulatory refrigerating systems, the combination with a base plate having a passage therethrough and a second plate parallel with the base plate and provided with a discharge valve, of an oscillatory piston, and a reciprocating and oscillatory cylinder block having opposite flat faces confined between the two plates and provided with an intake port on one of them movable into and out of register with the passage in the base plate to be opened and

closed thereby and with an exhaust port on the other controlled by the valve on the second plate.

5. In a gas compressor for circulatory refrigerating systems, the combination with a base plate having a passage therethrough and a second plate parallel with the base plate, of an oscillatory piston, a reciprocating and oscillatory cylinder block having opposite flat faces confined between the two plates and provided with an intake port on one of them movable into and out of register with the passage in the base plate to be opened and closed thereby and with an exhaust port on the other, and a spring pressed valve on the second plate having an extended flat surface providing a yielding bearing for the block 10 and controlling the exhaust port.

6. In a gas compressor for circulatory refrigerating systems, the combination with a base plate having a passage therethrough and a second plate mounted on the first plate in parallelism therewith of a wrist pin extending between the plates, an oscillatory piston mounted thereon, a reciprocating and oscillatory cylinder block having opposite flat faces confined between the two plates and provided with an intake port on one of them movable into and out of register with the passage in the base plate to be opened and closed thereby and also provided with an exhaust port, and means controlling the exhaust port.

7. In a gas compressor for circulatory refrigerating systems, the combination with a base plate having a passage therethrough and a second plate mounted on the first plate in parallelism therewith; of an oscillatory piston, a reciprocating and oscillatory cylinder block having opposite flat faces confined between the two plates and provided with an intake port on one of them movable into and out of register with the passage in the base plate to be opened and closed thereby and also provided with an exhaust port, means controlling the exhaust port, a crank shaft having a bearing in the second plate and having a crank pin connected to the cylinder block, and a motor supported on the said second plate for driving the shaft.

8. In a gas compressor for circulatory refrigerating systems, the combination with a piston and cylinder couple having relative movement combining reciprocation of the one with oscillation of the other, the cylinder being provided with an exhaust port and an intake port, of a controlling means for each of said ports, a motor connected to move the couple relatively, said cylinder being also provided with a bypass port, a valve normally opening the bypass port while the compressor is at rest, and means operated by the motor upon the first few revolutions thereof for actuating the valve to close the bypass port.

9. In a gas compressor for circulatory refrigerating systems, the combination with a piston and cylinder couple having relative movement combining reciprocation of the one with oscillation of the other, the cylinder being provided with an exhaust port, with an intake port and with a bypass port, of controlling means for the intake and exhaust ports, a motor connected to move the couple relatively, a source of oil supply, an oil pump connected therewith and operated by the motor, and a valve for closing the bypass port actuated by the oil pump through the medium of the oil.

10. In a gas compressor for circulatory refrigerating systems, the combination with a piston and cylinder couple having relative movement combining reciprocation of the one with

oscillation of the other, the cylinder being provided with an exhaust port, with an intake port and with a bypass chamber having a bypass, of controlling means for the intake and exhaust ports, a motor connected to move the couple relatively, a source of oil supply, an oil pump connected therewith and operated by the motor, and a piston valve reciprocable in the bypass chamber for closing the bypass port and actuated by the oil pump through the medium of the oil.

11. In a gas compressor for circulatory refrigerating systems, the combination with a piston and cylinder couple having relative movement combining reciprocation of the one with oscillation of the other, the cylinder being provided with an exhaust port, with an intake port and with a bypass chamber having a bypass, of controlling means for the intake and exhaust ports, a motor connected to move the couple relatively, a source of oil supply, an oil pump connected therewith and operated by the motor to deliver to the bypass chamber, a piston valve in the latter for closing the bypass port by the pressure from such oil, and a spring in the bypass chamber for returning the piston valve when the compressor is at rest.

12. In a gas compressor for circulatory refrigerating systems, the combination with a piston and cylinder couple having relative movement combining reciprocation of the one with oscillation of the other, the cylinder being provided with an exhaust port, with an intake port and with a bypass port, of controlling means for the intake and exhaust ports, a motor having a crank shaft connected to move the couple rela-

tively, a source of oil supply, an oil pump connected therewith and operated by the motor and also connected to deliver to the crank shaft bearing, and a valve for the bypass port actuated by the pressure of the oil between the pump and said bearing.

13. In a gas compressor for circulatory refrigerating systems, the combination with an oscillatory compression piston, and a reciprocatory and oscillatory cylinder block cooperating therewith provided with an exhaust port, with an intake port, with a bypass port and with an oil pump cylinder chamber, of controlling means for the intake and exhaust ports, a motor connected to operate the cylinder block relatively to the piston, a source of oil supply for the oil pump cylinder chamber, an oscillating piston rod operating in the latter, and a valve for closing the bypass port actuated by the oil pump through the medium of the oil.

14. In a gas compressor for circulatory refrigerating systems, the combination with an oscillatory compression piston, a reciprocatory and oscillatory cylinder block cooperating therewith provided with an exhaust port, with an intake port and with an oil pump cylinder chamber, of controlling means for the intake and exhaust ports, a motor having a crank shaft connected to operate the cylinder block relatively to the piston, a source of oil supply for the oil pump cylinder chamber, ducts connecting the latter with the bearing of the crank shaft, and an oscillating piston rod operating in the oil pump cylinder chamber.

FREDERICK J. HEIDEMAN. 35
